ABSTRACT: Leads for electronic components are provided with solder preforms by a method and apparatus which first cuts off a length of solder wire and then forms the wire into a preform and cold-welds it to the lead.

LEAD AND SOLDER PREFORM ASSEMBLY AND METHOD OF MAKING THE SAME

This invention is intended to provide leads for electronic components with solder preforms cold-welded to the areas at which the leads are to be attached to the component terminals. This eliminates the need for handling solder preforms.

In the drawing:

FIG. 1 is a diagrammatic elevation of an electronic component,

FIGS. 2, 3 and 4 are sectional views of apparatus for forming and cold-welding solder preforms to a lead, and

FIGS. 5-12 inclusive are views of some leads used for electronic components.

The component shown in FIG. 1 which may be a resistor, capacitor, etc., has a body 1 with end terminals 2, 3 which are to be soldered to the heads 4 of leads 5. This illustrates one of many common electronic components requiring leads.

By the apparatus and method shown in FIGS. 2, 3 and 4, a solder preform of the required size is formed and cold-welded to a lead at the location at which the soldered connection is to be made to the component terminal. The apparatus is shown applying the solder preform to the head 4 of the lead 5. The lead is gripped by a die having jaws 6, 7 with surfaces 8, 9 resting against the underside of the head 4 and providing a backup or supporting surface for the head. The solder preform is formed and attached to the head 4 by a punch comprising parts 10 and 11 connected to each other by a lost motion connection 12 such as the pin and slot connection illustrated. The part 10 has a bore or way 13 aligned with and receiving the head 4 and has an end surface 14 which butts or is stopped against the surfaces 8, 9 as the punch closes against the jaws 6, 7 by movement in the direction of arrow 15. As soon as the motion of the part 10 or housing of the punch is stopped by engagement with surfaces 8, 9, the part 11 of the punch continues its movement in the direction of arrow 15 and overcomes the pressure of spring 16 which normally holds the lost motion connection 12 between the parts 10 and 11 at the extreme left as shown in FIG. 2. Prior to the movement of the part 11 relative to the part 10, a length 17 of wire solder has been fed (by suitable means not shown) into the bore 13 through a way 17a transverse to the bore and in front of the section 18 of the part 11. During the initial movement of the part 11 relative to the part 10, the length 17 of solder wire is sheared off and upon continued movement in the direction of arrow 15, the sheared off length of solder wire 17 is formed into a preform 19 which is upset and cold-welded to the adjacent surface of the head 4. If the bore 13 is slightly oversize compared to the outside diameter of the head 4, some solder may be squeezed around the outside of the head as shown at 20 in FIG. 3. FIG. 4 shows the return stroke of the punch effected by movement of the part 11 in the direction of arrow 21. The lead with the solder preform 19 cold-welded to its head may now be removed from the jaws 6, 7 and soldered to one of the terminals 2, 3 of the component 1. The soldering may be carried out by any of the usual operations such as fluxing, heating in a reducing atmosphere, etc.

FIGS. 5-12 inclusive indicate various leads to which solder preforms may be cold-welded. The leads are of metals suitable for soldered connections such as copper, nickel, copper-coated steel. The leads may also be of glass-sealing alloys having coefficients of expansion matching the coefficients of expansion of specific glasses. Among these glass-sealing alloys

are Invar, Kovar.

The shape of the wire is not critical. FIGS. 5, 6, 7, 9 and 10 show round wire 23, 24, 25. FIGS. 8 and 12 show square wire 26. Nor is the shape of the head of the lead critical. FIGS. 5 and 9 show a wire with a round head 27. FIGS. 6 and 10 show wire with a square head 28. Nor is it necessary that the wire be headed. FIGS. 7, 8, 11 and 12 show wire without a head. In this case, the solder preform would be attached directly to one end of the lead and would usually be coextensive with the lead end. No effort has been made to illustrate all possible shapes of wire leads.

The die which applies the solder may also be used to form the head 4. In this mode of operation, the jaws 6, 7 grip the lead 5 a short distance from the end so sufficient wire to form the head 4 projects into the bore 13 when the punch 10, 11 is fully closed against the die. In this mode, the punch would have two strokes. The first stroke (without solder) would form the head 4. The second stroke (with solder) would cold-weld the solder to the freshly formed head, which would have a clean surface exposed to the solder to facilitate or promote welding. Also, the invention is not limited to feeding the solder in the form of wire. The die will cold-weld to the head 4 other precut or preformed shapes or measured quantities of solder placed in the bore 13 between the part 18 and the head 4.

We claim:

1. Apparatus for making a lead and solder preform assembly comprising a lead wire having an end surface transverse to the length of the wire to be soldered to a terminal and a solder preform attached to and overlying said surface for providing the solder for making a soldered connection from said surface to said terminal and eliminating the need for handling individual solder preforms at the time of making the soldered connection comprising members cooperating to define a die cavity, one member being a punch, the other member having means for supporting a lead wire having an end surface transverse to the length of the wire to be soldered to a terminal and to which a solder preform is to be attached so said surface is presented in said cavity to the punch, said punch having first and second parts, the first part being stopped against the other member and having a first way leading to said surface and slidably receiving the second part, means for retracting the second part relative to the first part to provide a space in said first way between said parts, means for feeding a portion of solder into said space in the first way ahead of the second part comprising a second way in the first part transverse to said first way and in front of the second part in the retracted position of the second part, said second part upon closing against the other member impacting the solder against said surface to shape the solder into a preform and cold-weld the same to said surface.

2. The apparatus of claim 1 in which the means for supporting the lead wire comprises jaws gripping the lead wire.

3. The apparatus of claim 2 in which the jaws have supporting surfaces for a head on the lead wire to which the solder preform is to be attached.

4. The apparatus of claim 1 in which the solder entering the first way is a wire and said second part upon closing against the other member first shears the solder fed through the second way into the first way and then impacts the sheared solder against said surface to shape the sheared solder into a preform and cold-weld the same to said surface.
